UNITED STATES PATENT OFFICE.

ALBIN WILBERG, OF DEKALB, ILLINOIS, has invented a new and useful Improvement in Combined Chucks and Countersinks.

Specification of Letters Patent. Patented June 23, 1914.

Application filed March 23, 1914. Serial No. 626,604. 111

To all whom it may concern:

Be it known that I, ALBIN WILBERG, a citizen of the United States, residing at Dekalb, in the county of Dekalb, and State of Illinois, have invented a new and useful Improvement in Combined Chucks and Countersinks, of which the following is a specification.

My invention relates to an improvement in combined chucks and countersinks for drill-stocks and boring machines and more particularly such as are used in wood-working.

In the accompanying drawing, Figure 1 shows my improved chuck by a view in sectional elevation, with the hollow stem or shaft broken away; Fig. 2 is a similar view with the drill removed, showing the bit-holding jaws and reamer-members expanded; Fig. 3 is a section on line 3, Fig. 1; Fig. 4 is a section on line 4, Fig. 1, and Fig. 5 is an enlarged broken view showing the cutting end of one of the reamer-members.

The shell 6 of the chuck, of cylindrical shape tapering toward one end, contains opposite slots 7, 7 where the taper begins; and the tapered section is provided in its outer surface with grooves 8, 8 extending from the slots to its opposite end. A sleeve 9, having a flanged cylindrical threaded head 10, from which it tapers inwardly, screws at the head into the outer end of the shell to abut its flange against the latter; and the interior of the tapered section of the sleeve, which contains an annular recess 11 in its extremity, is threaded, while similar diametrically-opposite recesses 12, 12 are provided in its outer walls and extend into the annular head 10. A tapering head for holding a drill 14 fits in the tapered end of the sleeve and is formed of similar sections 13^a held apart against the tapering sleeve-wall by springs 16 confined between them. Moreover the angle of taper of the inner wall-surface of the sleeve and outer surfaces of the sections 13^a is such as to cause the spreading action of the springs 16 on those sections to cause the holder 13 to tend to move upwardly in the sleeve. A tubular stem or shaft 17, provided with a circumferential protuberance 18, screws into the sleeve, affording its bearing, against an outwardly flanged collar 19, through the medium of which the stem bears with the least friction centrally against the wider end of the drill-holder; and the

diameters of the bore of the collar and stem should be alike, as shown.

In the shell-slots 7 are pivoted between their ends similar reamer-members 20, 20 diverging at their outer ends in the head 10 to prevent cam-like sections to the protuberance 18, and converging toward their opposite ends where the converging sections work and are guided in the grooves 8 and beyond which they terminate in more convergent sections provided on relatively opposite sides with cutting edges, like the one shown at 21 in Fig. 5. Springs 22 secured to the backs of the reamer-members 20 toward their outer ends, bear against the inner wall of the head 10 and tend to spread apart those members at their cutting-edges in opposition to the action of the protuberance.

By means of my improved chuck, the primary object of which is to provide, as a permanent fixture on and rotatable with the shell, a reamer for countersinking holes bored by the bit, the reamer-members are automatically adjusted with reference to drills of different diameters used in the chuck. Thus, for clamping in the holder 13 a drill 14 of any diameter up to one snugly fitting the bore of the stem 17, the stem is turned in the direction to unscrew or withdraw it from the holder 13, when the springs 16 cause the latter to move along the tapered section of the sleeve following the withdrawal of the stem, and spread apart the section 13^a until the central opening between them is sufficiently large to admit that drill. The extent of protrusion of the drill is, of course, according to the depth of hole it is required to bore. This withdrawing movement of the stem causes the springs 22 to act, by pressing the outer cam-sections of the reamer-members inwardly, to separate the cutting-edge sections of the same. By then turning the stem in the opposite direction, it drives the sections 13^a inwardly or forwardly along the tapering sleeve-section to clamp them about and hold the inserted drill. When a drill of the largest diameter which the chuck is adapted to take is inserted, the stem 17 is withdrawn to its fullest extent shown in Fig. 2, thereby bringing the flange of the collar 19 into the annular recess 9 and the inner end of the clamping-head coincident with the corresponding end of the tapered section of the shell.

As will be seen, from the foregoing de-

scription, the reamer always bears the same relation to the diameter of the drill whatever that diameter may be within the capacity of the chuck, whereby the reamer will 5 properly perform its countersinking action in any diameter of hole bored by the drill.

I realize that considerable variation is possible in the details of construction specifically shown and described, and I do not 10 intend by illustrating a single, specific or preferred embodiment of my invention to be limited thereto; my intention being, in the following claims, to claim protection upon all the novelty there may be in my 15 invention as broadly as the state of the art will permit.

What I claim as new and desire to secure by Letters Patent is:—

1. A combined chuck and countersink comprising a shell, a drill-holder in the shell, and a reamer supported in the shell and having a countersink member to extend beyond the holder and coöperate with a drill therein.

2. A combined chuck and countersink comprising a shell, a drill-holder in the shell, and a reamer comprising countersink members supported on the shell to extend along opposite sides of and beyond said holder 30 and having converging sections provided with cutting-edges to coöperate with a drill in said holder, said members being adjustable relative to the drill.

3. A combined chuck and countersink comprising a shell, a drill-clamping holder 35 adjustably supported in the shell, a countersink reamer comprising members supported in the shell and having converging forward sections provided with cutting-edges to co- 40 operate with a drill in said holder, and means for simultaneously adjusting said holder and reamer-members correspondingly with relation to drills of different diameters.

4. A combined chuck and countersink comprising a shell, a drill-clamping holder adjustably supported in the shell, a countersink reamer comprising members supported in the shell and having converging forward sec- 50 tions provided with cutting-edges to co- 50 operate with a drill in said holder, and a tubular threaded stem working in the shell

and engaging said holder and reamer-members to adjust them, by turning the stem, correspondingly with relation to drills of 55 different diameters.

5. A combined chuck and countersink comprising a shell, a drill-clamping holder adjustably supported in the shell, a countersink reamer comprising members adjustably supported on the shell to extend along opposite sides of said holder and having converging forward sections provided with cutting-edges to coöperate with a drill in said holder, and means for simultaneously adjusting said holder and reamer-members correspondingly with relation to drills of different diameters.

6. A combined chuck and countersink comprising a shell having a tapering forward section and provided with slots, a tapering drill-holder comprising spring-spread sections in said tapering section, a tubular threaded stem provided with a protuberance, a bearing in the sleeve, into 75 which the stem screws, and a countersink reamer comprising members pivotally supported in said shell-slots and having cam-like outer ends spring-pressed against said protuberance and forward ends provided with cutting-edges and converging toward a drill in said holder to coöperate therewith.

7. A combined chuck and countersink comprising a shell containing a threaded bearing and having a tapering forward section 85 containing slots, a tapering drill-holder comprising spring-spread sections in said tapering section, a tubular threaded stem working in the threaded bearing and provided with a protuberance, and a countersink reamer comprising members pivotally supported in said slots to extend at one side of their fulcrums in the shell wherein their outer ends diverge and are spring-pressed against said protuberance, and at the opposite side of their fulcrums along the tapered section of the shell, beyond which the forward ends of said members converge toward and are provided with cutting-edges to coöperate with a drill in said holder.

ALBIN WILBERG.
